HINGE CONSTRUCTION

Olof V. Anderson, Warwick, R.I., assignor to Anson Incorporated, Providence, R.I., a corporation of Rhode Island

Filed June 4, 1956, Ser. No. 589,218

6 Claims. (Cl. 16—159)

The present invention relates to improvements in hinge constructions and more particularly to an improved hinge construction which eliminates the use of and requirement for screws, nails, or similar items which are usually required for securing the hinge plates to the elements to be hingedly connected.

It is a primary object of the present invention to provide an improved hinge construction, the purpose of which is to hingedly join a pair of elements, wherein the hinge construction includes a pair of hinge plates pivotally joined together and at least one of the plates has means associated therewith which obviates the necessity for screws, nails, or similar attachment devices in attaching a hinge plate to an element to be hinged.

It is a further object of the present invention to provide an improved hinge construction wherein the means for securing the hinge plates to the elements to be hinged is of a simple nature, economical to manufacture and assemble, and yet which firmly and substantially non-releasably secures the hinge to the elements to be hinged.

Another object of the present invention is to provide an improved hinge construction for use in combination with a pair of elements to be hingedly connected wherein the hinge construction makes possible the molding of at least one of the elements to be hinged. In the case of a box or a top for a box, either part could be molded and one wall thereof formed with a recess which accommodates one of the hinge plates and its associated retainer means.

Still another object of the present invention is to provide an improved hinge construction which utilizes novel securing or retainer means for affixing at least one hinge plate to its respective element to be hinged wherein the novel means is of exceedingly light weight and yet exceptionally strong because of the manner in which it is associated with its cooperative element.

Another object of the present invention is to provide an improved hinge construction which employs novel means for securing at least one hinge plate to its respective element, which means is so associated with the hinge plate and element to be hinged as to give maximum resistance to separation.

Still another object of the present invention is to provide an improved hinge construction wherein in order to connect the element to be hingedly connected together it is merely necessary to insert each plate or at least one of the hinge plates into a slot formed in the element to receive the same. In this connection, the arrangement can be such that partial assembly can be effected, easy separation being possible because of the incomplete insertion of the hinge plate into its cooperative recess, whereby at a later time disconnection can be made if it is desired to associate different elements together than were originally associated with each other.

A further object of the present invention is to provide an improved hinge construction which is especially adapted for use in combination with boxes and covers or tops therefor wherein it might be desired to associate

2

any one of several different types or colors of covers or tops with a box. Thus, the goods to be sold in the box could be shipped therein with a cover associated therewith and the retailer could be provided with a number of different types and colors as far as the covers are concerned and the assembly of cover to box can be made by the retailer when a choice of style or color has been made by a customer.

A still further object of the present invention is to provide an improved hinge construction which requires but little modification of existing hinges and which is not materially more expensive than previous types of conventional hinges.

Various other objects and advantages will become apparent from the detailed description to follow.

In the drawings:

Figure 1 is a perspective view showing my improved hinge construction in exploded relation to one of the elements to be hinged, in this case a box;

Figure 2 is an exploded perspective view showing the elements which comprise my improved hinge construction;

Figure 3 is a front view of the hinge construction showing the novel strip associated therewith;

Figure 4 is a view taken substantially along the plane of line 4—4 in Figure 3;

Figure 5 is a front elevational view of the strip per se;

Figure 6 is a bottom plan view of the strip of Figure 5;

Figure 7 is a vertical sectional view through an assembly of my improved hinge construction and the box showing the cooperative relationship between the parts;

Figure 8 is a view similar to Figure 1 but showing a slightly different form of hinge construction;

Figures 9 through 12 are views similar to Figures 3 through 6 but showing the form of hinge construction of Figure 8;

Figure 13 is a vertical sectional view taken through my improved hinge construction and a portion of the element with which it is associated showing the manner in which the elements are cooperatively associated with each other;

Figure 14 is a view similar to Figure 13 but taken at a difference point along the length of the hinge;

Figure 15 is a view similar to Figure 1 but showing still another form of improved hinge construction;

Figure 16 is a front elevational view of the hinge construction showing the strip of Figure 15 in enlarged detail;

Figure 17 is a view taken substantially along the plane of line 17—17 in Figure 16;

Figure 18 is a front elevational view of the strip per se;

Figure 19 is an edge view of the strip of Figure 18 and showing in dotted lines the manner in which the end portions bow when the hinge is inserted into a cooperative slot;

Figure 20 is a horizontal sectional view through the end wall of the box of Figure 15 showing the manner in which the hinge construction cooperates with the slot;

Figure 21 is a vertical longitudinal sectional view through a portion of the wall of the box of Figure 15 showing the manner in which the hinge construction cooperates with the end walls of the slot; and

Figure 22 is a vertical transverse sectional view showing the manner in which the improved hinge construction of Figure 15 is received in the slot of the box.

Referring more particularly to the drawings, wherein like numerals apply to like parts throughout, it will be seen in Figure 1 that I have shown my improved hinge construction indicated generally by the numeral 10 in combination with a box 12 to which is to be hingedly connected a cover or top (not shown). It will be understood that although I have shown a box the elements

to be hingedly connected together may be other than a box and its cover as will readily be understood. For example, the improved hinge construction could be employed for hingedly securing a cabinet door to a cabinet or wherever two elements are desired to be hingedly connected together.

As shown best in Figures 2 through 6, the improved hinge construction 10 is comprised of a pair of hinge plates 14 and 16 pivotally connected together by a hinge pin 18, a spring 20 and a retainer means 22. While the hinge plates 14 and 16 are pivotally connected together by the hinge pin 18 as shown, it will be obvious that where desired other means for pivotally connecting the plates can be utilized without departing from the spirit and scope of the instant invention. The details of how the hinge plates 14 and 16 are pivotally connected are shown to be of conventional form and detailed description thereof is therefore deemed unnecessary. Each of the hinge plates 14 and 16 is formed with a cut-out portion 24 or 26 preferably at their centers and along their outside edges 28 and 30 for cooperation with the spring 20. The spring 20 is formed of resilient material and has an arcuate portion 32 terminating at its ends with reversely bent portions 34 and 36 which are adapted to be engaged with the edges of the cut-outs 24 and 26 as shown in Figures 3 and 7. As shown, the hinge construction 10 has its retainer means 22 associated with only one of the hinge plates 16 although it will be understood that where desired, both hinge plates can be formed for having retainer means associated therewith. The hinge plate 16 has in addition to its center cut-out 26 a pair of cut-outs 38 and 40 which are of substantially rectangular shape and which are located on opposite sides of the cut-out 26. Adjacent the ends of the hinge plate 16 are formed a pair of narrow slits 42 and 44 for a purpose presently to be described.

The retainer means 22 is preferably formed as a separate strip of resilient material thin enough to be easily manually flexed. The strip is of narrow elongated shape and has at its ends a pair of tabs 46 and 48 which are offset slightly from the plane of the strip as shown best in Figures 4 and 6. Thus, in order to secure the retainer means 22 to the hinge plate 16, it is merely necessary to bow the strip so that the tabs 46 and 48 can be inserted into the slits 42 and 44 and then released to assume the relationship shown in Figure 4. Along the edge 50 of the strip 22 and substantially at the center thereof a cut-out 52 is provided which substantially corresponds in shape to the cut-out 26 of the hinge plate 16 so that the spring 20 can have its terminal portion 36 engaged therethrough so as to hold the center of the strip 22 in association with the hinge plate 16 as shown in Figure 7. Also, the strip 22 is formed with a plurality of transversely extending slits 54 and 56 which open out at the edge 50. The slits 54 and 56 define a plurality of tongues or prong-like projections 58 and 60 which terminate in reversely bent pointed portions 62 and 64 best shown in Figures 5 and 6. As shown, the pointed end portions 62 and 64 are inclined with respect to the plane of the strip 22 and extend generally toward the hinge pin 18 or other pivotal interconnection for the plates 14 and 16.

Looking now at Figure 1, it will be seen that the box 12 is of substantially conventional rectangular dish shape except for its rear wall 66. The box 12 can be of molded construction since the slot 68, presently to be described, permits of such molding. The slot 68 in the wall 66 of the box 12 is of elongated shape opening out into the top surface 70 of the wall 66. At its center, the slot 68 opens to the interior of the box at the wall surface 72 so as to provide a cut-out at 74. Preferably, the inner surface of the slot 68 is formed with a plurality of ribs 76, 78, 80 and 82, the function of which is to minimize the relative play between the hinge and the box when assembled. In order to facilitate in-

sertion of the hinge plate 16 and strip 22 associated therewith into the slot 68, the hinge plate 16 may be formed with the guide noses 84 and 86.

Looking now at Figures 1 and 7, it will be seen that assembly of the hinge 10 to the box 12 is effected by insertion of the hinge plate 16 with its strip 22 into the slot 68. The spring 20 is received in the cut-out 74. As the hinge plate 16 and its strip 22 are inserted into the slot 68, it will be seen that the prong-like projections 58 and 60 with their pointed ends 62 and 64 will be deflected because the dimension "X" shown in Figure 4 is made to be greater than the dimension "Y" as shown in Figure 7. Because the prong-like projections 58 and 60 are disposed in cooperative relationship with the cut-outs 38 and 40, the difference in the dimensions of "X" and "Y" forces the prongs to be deflected as shown in Figure 7. Moreover, it is to be especially noted that the length of the pointed ends 62 and 64 is such as to be greater than the dimension "Y." Thus, if after insertion, it is attempted to remove the hinge 10 from the box 12, the pulling force exerted on the strip 22 will tend to pull the bearing portion 84 against the interior wall surface 86 of the slot 68 while the pointed end bites in at 88 into the interior wall surface 90 of the slot 68 thus creating a wedging action which rigidly withstands the application of removal forces on the hinge.

In the construction shown in Figures 8 through 14, the hinge 10 and box 12 are of the same construction as shown in Figures 1 through 7 with the exception of the formation of the strip 22' which will now be described. Instead of forming the strip 22' with only a pair of prong-like projections as in the previous species, the strip 22' is formed with three prong-like projections at each side of the center cut-out 52 as shown at 92 and 94. Two of the prong-like projections of each group 92 and 94 are shown with their pointed ends 96 and 98 reversely bent on one side of the strip 22' while the pointed ends 100 and 102 are reversely bent on the opposite side of the strip 22'.

As shown in Figures 13 and 14, the assembly of the hinge 10 into the slot 68 of the box 12 is made in substantially the same way as shown in Figure 7. However, it will be noted that because the utilization of prong-like projections which terminate in pointed ends directed oppositely from each other, the middle pointed ends 100 and 102 will be directed through the cut-outs 38 and 40 so as to engage the interior wall surface 86 of the slot 68 as shown in Figure 13 while the other pointed ends 96 and 98 will be directed against the interior wall surface 90 as in the previous embodiment. The resistance of the assembly to withdrawal from the slot 68 will thus be heightened by the arrangement of the prong-like projections with respect to the slot 68.

Looking now at Figures 15 through 22, the third species of hinge construction will now be described. Inasmuch as the box 12 which is shown by way of example, is the same as in the previous embodiments, no further description thereof is deemed necessary. However, the hinge construction 10' differs from those of the previous embodiments in that the hinge plate 16' and strip 22" are of somewhat different formation. The hinge plate 16' is formed with the center cut-out 26 but omits the other cut-outs along the edge 30 and instead of having slits formed adjacent its ends as in previous embodiments, the hinge plate 16' has a pair of slits 104 and 106 spaced substantially inwardly from the ends thereof.

The strip 22" which cooperates with the hinge plate 16' is formed from resilient material and is of narrow elongated shape having a cut-out at 52 corresponding to those of the previous embodiments. However, instead of having end tabs, the strip 22" has formed inwardly from its ends a pair of tabs 108 and 110 which are struck out from the material of the strip and are outwardly bent as shown in Figure 19. The strip 22" has its end edges formed with a saw-tooth formation 112

and 114 which correspond to the prong-like projections of the previous embodiments. In this embodiment, the overall length of the strip 22' is selected so as to be slightly longer than the length of the slot 68. The strip 22" is mounted on the hinge plate 16' by bowing the central portion between the tabs 108 and 110 so that the tabs can be inserted into the slits 104 and 105. Thereafter, in order to effect the assembly, reference being had to Figures 20 through 22, the hinge plate 16' with the strip 22" associated therewith is inserted into the slot 68 of the box and because of the bevel of the teeth as shown at 116 and 118, the strip 22" is received within the slot 68 notwithstanding the fact that the strip is longer than the slot. To further facilitate insertion of the assembly into the slot 68, the resilience of the strip is such that the portion thereof outwardly of the tabs 108 and 110 bows as shown in Figure 20 to reduce the length thereof substantially to that of the slot 68. The saw-tooth ends of the strip prevent removal of the hinge from the box and provide an effective mode of attachment.

In view of the foregoing it will be seen that I have provided an improved hinge construction which accomplishes all of the objects hereinbefore discussed. Inasmuch as it is impractical to make conventional hinges, such as with the hinge pin, from material which is sufficiently thin and resilient to be flexible for necessary functioning as in the assemblies hereinbefore described, it will be seen that I have provided a unique hinge construction which is susceptible of embodiment in many forms.

As this invention may be embodied in several forms without departing from the spirit or essential characteristics thereof, the present embodiment is therefore illustrative and not restrictive, since the scope of the invention is defined by the appended claims rather than by the description preceding them, and all changes that fall within the metes and bounds of the claims or that form their functional as well as conjointly cooperative equivalents, are therefore intended to be embraced by these claims.

I claim:

1. A hinge construction comprising a pair of plates pivotally connected together, each of said plates being adapted to be secured to a respective element to be hinged, retainer means associated with each of said plates for securement thereof with its respective element, at least certain of said retainer means comprising a separate strip of relatively thin resilient material formed with a plurality of prong-like projections directed generally toward the pivotal connection of the plates, and means securing said certain retainer means to a respective plate.

2. A hinge construction comprising a pair of plates pivotally connected together, each of said plates being adapted to be secured to a respective element to be hinged, retainer means associated with each of said plates for securing thereof with its respective element, at least certain of said retainer means comprising a separate strip of relatively thin resilient material formed with a plurality of prong-like projections directed generally toward the pivotal connection of the plates, said prong-like projections being inclined with respect to the plane of the respective plate, and means securing said certain retainer means to a respective plate.

3. A hinge construction comprising a pair of plates

pivotedly connected together, each of said plates being adapted to be secured to a respective element to be hinged, retainer means comprising at least one strip of relatively thin resilient material, each strip including tabs securing the strip to one of said plates, and said strip having a plurality of prong-like projections directed generally toward the pivotal connection of the plates and inclined with respect to the plane of its respective plate for securement thereof with its respective element.

10 4. A hinge construction comprising a pair of plates pivotally connected together, each of said plates being adapted to be secured to a respective element to be hinged, retainer means comprising at least one strip of relatively thin resilient material, each resilient strip including tabs 15 securing the strip to one of said plates so as to provide for limited relative movement between each strip and its respective plate and permit manual attachment of the strip to its respective plate, and each strip having a plurality of prong-like projections directed generally toward 20 the pivotal connection of the plates.

5. A hinge construction comprising a pair of plates pivotally connected together, each of said plates being adapted to be secured to a respective element to be hinged, retainer means associated with each of said plates for securing thereof with its respective element, at least one of said retainer means comprising a strip of relatively thin resilient material formed with a plurality of prong-like projections at least part of each of which is directed generally toward the pivotal connection of the plates and inclined with respect to the plane of the respective plate, said plate having the strip associated therewith being provided with at least one cut-out at the location of at least one prong-like projection so as to provide a recess into which the latter can be deflected so as to divert said part to its retaining position.

vert said part to its retaining position.

6. A hinge construction comprising a pair of plates pivotally connected together, each of said plates being adapted to be secured to a respective element to be hinged, retainer means associated with each of said plates for 40 securing thereof with its respective element, at least one of said retainer means comprising a relatively thin strip of resilient material formed with at least one prong-like projection, a first part of each of which projection extends generally away from the hinge pin and is substantially coplanar with its respective plate and a second part of each of which is reversely directed generally toward the pivotal connection of the plates and is inclined with respect to the plane of its respective plate, said plate 45 having the strip associated therewith being provided with at least one cut-out at the location of at least one prong-like projection so as to provide a recess into which the latter can be deflected so as to divert said second part to 50 its retaining position.
